S. SCHWARTZ.

COLLAR.

APPLICATION FILED DEC 28, 1921.

1,432,126.

Patented Oct. 17, 1922.

INVENTOR
Samuel Schwartz
BY
Mark H. Bloch
ATTORNEY, S.

UNITED STATES PATENT OFFICE.

SAMUEL SCHWARTZ, OF ALBANY, NEW YORK.

COLLAR.

Application filed December 28, 1921. Serial No. 525,294.

To all whom it may concern:

Be it known that I, SAMUEL SCHWARTZ, a citizen of the United States, residing at 144 Washington Avenue, Albany, in the 5 county of Albany and State of New York, have invented certain new and useful Improvements in Collars, of which the following is a specification.

My invention relates to a new and improved construction of collar.

One of the objects of my invention is to provide a new and improved type of soft collar.

Another object of my invention is to provide a new and improved type of soft collar which shall have a proper degree of stiffness and which will require no starching.

Another object of my invention is to provide a new and improved form of soft or 20 un-starched collar which shall be free from objectionable bulging seams.

Another object of my invention is to provide a new and improved type of soft collar which can be readily made in a variety of 25 shapes.

Another object of my invention is to provide a new and improved type of soft collar which can be quickly and economically manufactured with existing types of machinery, and can be readily laundered and ironed.

Other objects of my invention will be set forth in the following description and drawing which illustrate a preferred embodiment 35 of my invention.

Fig. 1 is a view of my improved collar laid flat, part thereof being shown removed, so as to more clearly illustrate the details of construction.

Fig. 2 illustrates the two blanks from 40 which the fold over top and neck band portions of my collar are made, but omitting the facing strips.

Fig. 3 is a section on the line 3—3 of 45 Fig. 1.

Fig. 4 illustrates another embodiment of my invention.

In the embodiment shown in Figs. 1, 2 and 3 the collar is made substantially of a 50 fold over top portion and a neck band portion, and two edge or face pieces for the said neck band portion. The neck band

portion 1, is preferably cut as shown in Fig. 2 so that the part thereof which is at the top of the completed collar is provided with an off-set or indented portion or recess 1^a. In this manner shoulders 1^b are formed adjacent the ends of the neck band portion. As clearly seen in Fig. 2, this off-set or indented portion 1^a is not symmetrically disposed, since it is nearer one end of the collar than the other. The fold over top portion 2 of the collar which may be cut in any desired shape, is of such length that it fits snugly between the shoulders 1^b of the neck band into the indentation or recess 1^a before mentioned. If desired, the neck band 1 may be of heavier material than the fold over top portion 2. As indicated more clearly in Fig. 1 three of the edges of the fold over top portion are turned under and secured by lines of stitching 3, as shown in Fig. 1. There are preferably two of these lines of stitching, one line being directly adjacent the edge of the said fold over top and the other line being substantially parallel and interior with respect to the first mentioned line of stitching. In this manner the turned under portions are firmly secured in place and they stiffen three of the 75 sides of the said fold over top, that edge of the fold over top portion which is directly connected to the neck band being left of a single thickness and un-stiffened. The un-stiffened edge of the fold over top portion is now placed directly in edge abutment against the indented part 1^a of the neck band, but not over-lapping the same, and the fold over top portion and neck band are then connected by zig-zag stitching 4 80 which may be done by many well-known types of sewing machines on the market, so that this stitching 4 firmly connects the neck-band and fold-over top without providing an objectionable bulging seam, having more than a single layer or thickness of fabric because of the edge abutment. This 85 is very important because since the collar has only a single thickness along the line of junction or fold between the fold over top portion and the neck band, it can be easily laundered and ironed, while it does not tend to sag or wilt if the collar becomes moistened by perspiration or the like.

As shown more particularly in Figs. 1 and 3, the neck band 1 has the opposite sides thereof covered by two facing strips 5, which have substantially the same construction. As shown more clearly in Fig. 3, each facing strip 5 has a turned under edge at the top and bottom edges thereof, whereby each facing strip can be formed of relatively very thin material, even thinner than the 10 fold over top or the neck band, as the facing strip has a double layer or thickness adjacent the bottom of the neck band and it also has a double thickness adjacent the line of junction between the fold over top and the 15 neck band. The facing strips 5 are secured to both the fold over top and to the neck band of the collar by lines of stitching 6. The uppermost line of stitching is located above the zig-zag stitching 4 and the lowermost stitching 6 is located at about the bottom or a little below the zig-zag stitching 4. This equalizes the layers or thicknesses of 20 the completed collar, so that it can be easily sewed in the flat condition and it also can 25 be easily laundered and ironed.

In my completed collar the bottom of the neck band has four layers, namely two layers of each of the thin facing strips 5. The collar has five layers at the line of junction 30 between the fold over top and the neck band and it is to be noted that the fold over top is folded at the uppermost line of stitching 6, so that the fold over top of the collar is not folded at the zig-zag stitching 4. 35 This enables the collar to be easily ironed and laundered and causes it to keep its shape substantially permanently.

In the construction shown in 4, the only 40 difference is that the fold over top and the neck band may be cut out of a single piece of fabric F, with an elongated space 8, between them. Of course the fabric can be 45 cut into two pieces which should be sewed together so as to have the contour shown in Fig. 4.

Here again the fold over top and the neck band have a single thickness of fabric when 50 they are sewed together without any objectionable thick seams, and when the basic portions of the collar are thus assembled the edge pieces are applied in the manner before described.

I have shown a preferred embodiment of 55 my invention, but it is clear that numerous changes and omissions can be made without departing from its spirit.

In the embodiment shown in Fig. 4, the adjacent edges of space 8 are caused to meet, so as to shape the collar.

60 It is to be noted that the neckband and fold over top which are made of relatively heavy material have a butt joint at their line of junction, so that they form practically a single thickness throughout.

65 I claim:—

1. In a collar, a fold over top, a separate neckband member made of a separate piece of material, said fold over top and neckband member being directly connected to each other by a line of stitches adjacent 70 their line of junction, the adjacent edges of said fold over top and said neckband substantially abutting each other along said line of junction so as to have practically a single thickness, and facing fabric covering 75 said line of stitches.

2. In a collar, a fold over top, a separate neckband member made of a separate piece of material, said fold over top and said neckband member being directly connected 80 to each other by a line of zig-zag stitches adjacent their line of junction and going alternately from one said part to the other, the adjacent edges of said fold over top and of said neckband substantially abutting each 85 other along said line of junction so as to have practically a single thickness, and facing fabric covering said line of stitches.

3. In a collar the combination of a neckband having a recess in one edge thereof 90 and extending through sufficient of the entire thickness of said neckband to form a sharply defined inner edge and a fold over top connected to said neckband and fitting into the said recess and substantially abutting 95 the inner edge of said recess so as to substantially form a butt joint at this point so that the junction of said neckband and fold over top produces practically a single layer at the line of junction thereof and 100 facing fabric covering said line of junction.

4. In a collar the combination of a neckband having a recess in one edge thereof and extending through sufficient of the entire thickness of said neckband to form a 105 sharply defined inner edge and a fold over top connected to said neckband and fitting into the said recess and substantially abutting the inner edge of said recess so as to substantially form a butt joint at this 110 point so that the junction of said neckband and fold over top produces practically a single layer at the line of junction thereof, said fold over top being folded over on a line spaced from said line of junction. 115

5. In a collar, a fold over top and a neckband connected by stitches along their adjacent edges said fold over top and said neckband practically abutting each other, and facing strip for said neckband extending 120 over said adjacent edges of said fold over top and said neckband and sewed to said fold over top and said neckband.

6. In a collar, the combination of a neckband having a recess formed in one edge 125 thereof, a fold over top fitting into the said recess and having turned under edges, the said fold over top and neckband being directly connected by zig-zag stitching, and facing strips having turned under edges and 130

connected to said neckband and to said fold over top by stitches.

7. A collar comprising a fold over top and a neck band, said neck band having its 5 edges unturned and of a single thickness, each side of the neck band having a facing strip provided with turned under edges em- bracing and secured to both longitudinal edges of the said neck band and covering said unturned edges. 10

In testimony whereof I hereunto affix my signature.

SAMUEL SCHWARTZ.
